[57] CLAIM

The ornamental design for a connector housing, substantially as shown and described.

DESCRIPTION

FIG. 1 is a top plan view of the connector housing showing our new design;

FIG. 2 is a front elevational view thereof;

FIG. 3 is a cross-sectional view thereof, taken along line 3—3 of FIG. 2;

FIG. 4 is a right side elevational view thereof; the left side being a mirror image;

FIG. 5 is a bottom plan view thereof;

FIG. 6 is a rear elevational view thereof;

FIG. 7 is a reduced perspective view thereof with the headlamp and associated structure being shown in broken lines for illustrative purposes only.

FIG. 3

FIG. 2

FIG. 1

FIG. 6

FIG. 5

FIG. 4

FIG. 7
